239,056

HAND-HELD VIEWER FOR MICROFORMS

Robert G. Holliday, Ann Arbor, Mich., assignor to
Xerox Corporation, Stamford, Conn.

Filed Mar. 25, 1975, Ser. No. 561,806

Term of patent 14 years

Int. Cl. D16—04; D24—02
U.S. Cl. D61—1J

Fig. 1.

Fig. 2.

Fig. 3.

Fig. 4.

Fig. 5.

Fig. 6.

Fig. 7.

FIG. 1 is a perspective view of a hand-held viewer in a closed position;

FIG. 2 is a front elevation view of the hand-held viewer in an opened position;

FIG. 3 is a top plan view of the hand-held viewer;

FIG. 4 is a bottom plan view of the hand-held viewer;

FIG. 5 is a right side elevation view of the hand-held viewer in an opened position;

FIG. 6 is a rear elevation view of the hand-held viewer in an opened position; and

FIG. 7 is a left side elevation view of the hand-held viewer in an opened position.

I claim:

The ornamental design for a hand-held viewer for microforms, substantially as shown and described.
